UNITED STATES PATENT OFFICE.

JOHN B. OWENS, OF METUCHEN, NEW JERSEY.

COOLING MEANS FOR TUNNEL-KILNS.

1,379,714.

Specification of Letters Patent.

Patented May 31, 1921.

Original application filed July 15, 1916, Serial No. 109,511. Divided and this application filed August 14, 1918. Serial No. 249,826.

To all whom it may concern:

Be it known that I, JOHN B. OWENS, a citizen of the United States, residing at Metuchen, in the county of Middlesex and 5 State of New Jersey, have invented certain new and useful Improvements in Cooling Means for Tunnel-Kilns, of which the following is a specification.

This invention relates to cooling means 10 for tunnel kilns and this application is a division of my application for kilns, Serial No. 109,511, filed July 15, 1916.

In a tunnel kiln, the ware having passed through a high temperature, and being 15 burned, in the burning or firing zone, it must cool gradually to prevent destruction of, or damage to, the ware but such cooling must be sufficiently rapid to insure adequate production by the kiln of the ware treated.

20 The object of the present invention is to provide improved cooling means in a tunnel kiln which will enable the ware to be cooled at a relatively rapid rate without damage thereto by utilizing the heat radiated from 25 the burned ware to the end that it is carried off without cool air coming in direct contact with the ware. The ware, being thus deprived of its heat, absorbed during the burning or firing operation, cools rapidly and 30 without damage.

The practical embodiment of my invention comprises air spaces in the walls of the cooling zone of the tunnel, provided with air inlets for outer, cool air to be admitted 35 to their lower portions, and outlets for voiding air from their upper portions. Either a natural draft, or an induced draft, may be employed in connection with the air spaces. The ware, previously burned in the firing 40 zone, having reached the cooling zone of the tunnel kiln, the heat radiated from the ware against the inner faces of the tunnel walls is carried off by the cool air passing upwardly in the air spaces in said walls. This 45 cool air, by reason of its upward circulation, cools the inner walls of the tunnel, and the heat radiated from the ware is attracted to the inner wall and carried off.

The construction used for providing the 50 air spaces or air channels in the walls of the tunnel at the cooling zone may be varied. Such spaces or channels may be provided within the walls themselves, or, as separate ducts or conduits. I do not, therefore, limit 55 myself to the precise embodiment of the in-

vention hereinafter described and which is shown in the drawings and the same is to be considered as illustrative, instead of restrictive, of the scope of the invention.

In the accompanying drawings:

Figure 1 is a side elevation of a tunnel kiln which is provided with my invention;

Fig. 2, is a transverse sectional view taken through the cooling zone on the plane indicated by the line 2—2 in Fig. 1; and

Fig. 3 is a horizontal sectional detail view taken on the line 3—3, Fig. 2.

To illustrate the position my improvements occupy in a tunnel kiln, I have shown in Fig. 1 the side of a tunnel kiln A having 70 air locks 18 and 19 at its entrance and exit ends, respectively, provided with movable gates, not shown, which may be raised and lowered, as desired, and provided with cables 21 and counterweights 22.

The drying zone is shown, generally, at 23, the burning zone at 30, furnace at 31, and the cooling zone to which my improvements apply, at 43.

The cars which convey the goods or ware 80 through the kiln from left to right, Fig. 1, travel on rails 57, Fig. 3.

Any suitable stack or draft inducing means, not shown, may be employed to afford the requisite draft necessary in a kiln of this 85 character.

Any suitable fuel may be used for the furnace 31. There is shown means for utilization of producer gas supplied by a main 32 to branches 33, 35 which lead to the furnace 90 where the gas is burned.

My improvements relating to the cooling zone will now be described, said improvements constituting the present invention.

The walls of the cooling zone 43 are lined 95 with hollow construction 44, producing vertical tubes or ducts 45 that communicate at their lower ends with air inlets 46 in the side walls of the kiln, Figs. 2 and 3, the upper ends of the tubes or ducts 45 communicating with openings 47 in the lower roof arch 48 which is separated by an intervening space 49 from the upper roof arch 50 which has one or more outlets 51, permitting a circulation of air which will 100 reduce the temperature of the cooling zone, thereby permitting the ware to become gradually cooled during its passage through said zone and prior to its discharge through the air lock 19.

Circulation through the ducts 45 and the space 49 may be accelerated by supplying air under pressure, as by means of a blower, conventionally indicated at 49^b in Fig. 2, 5 or in other convenient manner. The effect of this would be to cool the burned material more rapidly and to produce a larger supply of heated air for other purposes.

The outlet 51 may communicate with 10 ducts 38 for the purpose of conveying to the furnace 31 the air which has become heated during its passage through the ducts 45. The circulation through ducts 38 may be induced or forced.

15 The ware, previously burned in the firing zone having reached the cooling zone 43, the heat radiated from the ware against the inner faces of the ducts 45 through which cool air is traveling upwardly, is carried off by the cool air in said ducts and passes out through the outlet or outlets 51, either to the air, or to any suitable point. The cool air in the ducts 45 cools the inner walls of the tunnel throughout the 25 cooling zone 43 and the heat radiated from the ware is attracted to the inner walls of aforesaid and is carried off, sufficiently slowly to prevent damage to the ware and yet with such rapidity that the ware is cooled with a speed suitable to insure relatively rapid output of cooled ware from the kiln on operation of the air lock 19. The arch 48 completely seals the cooling zone 43 from the outer air and from the space 35 49. There is no direct outer-air inlet into the cooling zone, nor any direct air-outlet from said zone to chill the ware. The cooling action is solely an indirect one and yet is relatively rapid.

40 Whether the tubes or ducts 45 are provided in the walls of the cooling zone, or in a hollow construction arranged as a lining therefor, the numerous ducts divide up the air into numerous streams, facilitating 45 the cooling action.

What I claim is:

1. A tunnel kiln having a furnace for delivering heat into the interior of its tunnel

and provided with a sealed cooling zone 50 whose side walls are provided with air circulating spaces sealed from the interior of the cooling zone, said spaces being adapted to receive outer air at their lower parts, and to void the air at their upper parts, and being arranged and adapted for the upward 55 passage of the outer air for the purpose of cooling the inner tunnel walls and taking off the heat radiated from the ware within the cooling zone without direct entry of air into said cooling zone or direct exit of air 60 therefrom.

2. A tunnel kiln having a furnace for delivering heat into the interior of its tunnel and provided with a sealed cooling zone 65 whose side walls are provided with numerous air circulating ducts sealed from the interior of the cooling zone, said ducts being adapted to receive outer air at their lower parts, and to void the air at their upper parts, and being arranged and adapted for 70 the upward passage of the outer air for the purpose of cooling the inner tunnel walls and taking off the heat radiated from the ware within the cooling zone without direct entry of air into said cooling zone or direct 75 exit of air therefrom.

3. A tunnel kiln having a furnace for delivering heat into the interior of its tunnel, a sealed cooling zone whose side walls are provided with air circulating spaces sealed 80 from the interior of the cooling zone, said spaces being adapted to receive outer air at their lower parts, and to void the air at their upper parts, and being arranged and adapted for the upward passage of the outer 85 air for the purpose of cooling the inner tunnel walls and taking off the heat radiated from the ware within the cooling zone without direct entry of air into said cooling zone or direct 90 exit of air therefrom, and means for conducting the voided heated air from said air circulating spaces to the furnace of the kiln.

In testimony whereof I affix my signature.

JOHN B. OWENS.
